ROLLING MILL

Florence C. Biggert, Jr., Crafton, Pa., assignor to
 United Engineering & Foundry Company,
 Pittsburgh, Pa., a corporation of Pennsylvania

Application August 13, 1932, Serial No. 628,675

29 Claims. (Cl. 80—56)

My invention relates to rolling mills, and particularly to rolling mills for producing relatively thin sheets of metal.

In the operation of rolling mills for producing relatively thin sheet metal, difficulty has been encountered in securing sheets of uniform thickness and within the limits of tolerance usually permitted. Such difficulties have resulted from a number of causes, including the elasticity of 5 the materials constituting the rolls, bearing blocks and the roll housing of the mill.

This elasticity or "stretch" has permitted the rolls and bearing blocks to be bent or compressed when the metal is being rolled and at the same 15 time has permitted portions of the housing to elongate while other portions such as the top and the bottom deflect as beams. The result has been that the adjustment of the rolls prior to the entering of the metal to be rolled is not an accurate measure of the thickness of the finished 20 metal by reason of the changes occurring in the dimensions of the various parts of the mill when the metal enters the rolls.

Furthermore, breakages have occurred when 25 the metal to be rolled, by reason of its temperature or other conditions causes forces to be set up within the rigidly adjusted mill that are beyond the strength of the materials for resisting them.

30 In order to materially diminish the variations in dimensions and other inaccuracies with respect to the sheets of metal produced, I propose to place the housing and the bearing blocks of the mill under initial stress by means of hydraulic cylinders or other fluid-pressure devices, this pressure exceeding that normally encountered 35 in the operation of the mill for rolling metal. I also provide that the parts of the mill within which changes in stresses occur when a piece of metal enters the rolls occupy relatively 40 short spaces whereby the effect of these changes is correspondingly diminished.

The pressure thus initially applied places the 45 bearing blocks for the backing rolls and the housing under stresses greater than those caused by metal between the rolls and the effect is much different than if the stresses were caused by the working pressures of the rolls of the mill. By reason of the application of these 50 initial stresses the entrance of the metal causes substantially no additional elongation of the housing and the bearing blocks for the backing rolls are not substantially compressed further. When metal enters the working rolls, the effect 55 is to relieve the bearing blocks and spacing

blocks therebetween of a portion of the stress thereon and to transfer it to the working rolls and the backing rolls therefor.

The result is to initially elongate the housing and to deflect the parts acting as beams to an extent that will not be appreciably altered during the operation of the mill, the pressure being maintained constant both before and after the metal enters the rolls. This arrangement has been found to eliminate the major portion of the 60 variations in thickness of the metal after the 65 rolls have been adjusted.

The provision of fluid-pressure devices for placing the bearing blocks under compression has also eliminated breakages of the rolls or of the 70 housing by reason of the fact that the fluid-pressure devices permit the rolls and the bearing blocks to yield in case of excessive hardness of the metal being rolled or any other occurrence that might otherwise cause breakage. In such 75 case, the source of fluid pressure maintains a constant pressure upon the mill, regardless of the positions of the bearing blocks and the rolls.

In rolling mills of the prior art, the housing has been placed under stress that is either dependent upon or is set up by the rolling pressure or reactions therefrom but only while the mill 80 is rolling metal. Such stress can not be applied to stretch the housing before metal enters the rolls nor can it exceed the rolling pressure. 85 There will therefore be material variations in the dimensions of the mill when metal enters the rolls.

Instead of the usual screw-down mechanisms employed for adjusting the distances between 90 the rolls and the resultant thickness of material rolled by the rolling mill, I employ wedges, the longitudinal position of which determines the distances between the bearing blocks for the backing rolls of a mill and thereby determines 95 the distance between the working rolls and, accordingly, the thickness of the resulting sheet metal. In order to insure that both ends of the rolls are adjusted for the same thickness of metal, I have arranged that the wedges for each 100 end of the roll may be adjusted either simultaneously or independently in case of a variation in relative position of the wedges for the respective ends.

An important feature of the arrangement of 105 the screw-down mechanism is that it is located entirely on the driving side of the mill and the other side of the mill is entirely unobstructed for the removal or replacement of rolls.

In order to easily and quickly determine any 110

variation in relative position of the wedges at the respective ends of the rolls, I provide an indicating mechanism which indicates the relative positions of the wedges at the respective ends 5 of the rolls and which also indicates the thickness of metal for which the rolls are adjusted.

The details of my invention will be described in connection with the accompanying drawings, in which Fig. 1 is an end elevational view of a 10 rolling mill constructed in accordance with my invention, parts being shown in section.

Fig. 2 is a front elevational view of the rolling mill of Fig. 1.

Fig. 3 is an enlarged elevational view of the 15 wedge operating mechanism, parts being broken away.

Fig. 4 is a view partially in end elevation and partially in vertical section of a portion of the mill of Fig. 1.

20 Fig. 5 is a view similar to Fig. 4 but taken at right angles thereto.

Fig. 6 is an enlarged view in vertical section taken on line VI—VI of Fig. 3.

25 Fig. 7 is an end elevational view of the wedge operating mechanism of Fig. 3.

Fig. 8 is a front elevational view of a portion of the mill of Fig. 1 with the indicating mechanism in position; and

30 Fig. 9 is a view in end elevation of the mill of Fig. 1 illustrating a portion of the indicating mechanism, the rolls of the mill being shown diagrammatically, and parts being broken away.

A rolling mill constructed in accordance with my invention comprises a frame 1, which consists of a base structure 2, upon which is mounted two vertical rectangular roll housings or side frames 3. Each housing 3 comprises two vertical posts 4 that are connected by a top 5. The housings 3 are indirectly connected through blocks 12 at both their front and rear portions by horizontally extending brackets 6.

The rolls are arranged for a four-high mill and comprise two relatively large backing rolls 7 and 8 and two relatively small working rolls 9 and 10. Within the rectangular space of each of the housings 3 are mounted bearing blocks 12 and 13 for the respective ends of the backing rolls 7 and 8. These blocks are held in place between the vertical posts 4 by means of clamping plates 14 having bolts 15 that extend through slotted openings 16 whereby the clamps may be moved into and out of clamping position.

Between the upper and the lower bearing blocks 12 and 13 and at each end of the latter are two blocks 17 and 18 that have substantially cylindrical adjacent surfaces, as best shown in Figs. 2 and 5, and that have a tongue-and-groove connection at 19 as shown in Fig. 4. The blocks 17 and 18 are held in position between the bearing blocks 12 and 13 by means of outer flanges 20 projecting vertically from the bearing blocks 12 and 13 and are held in their spaced positions by means of projections 21 on the respective blocks 12 and 13.

In the recesses formed by the spaces between the respective pairs of blocks 17 and 18 are mounted bearing blocks 22 and 23 for the respective working rolls 9 and 10. The bearing blocks 22 and 23 are held in position axially of the rolls by means of clamps 24 that are provided with bolts 25 and slotted openings 26 similar to those of the clamps 14. Each clamp projects into a groove 27 in the respective blocks.

Hydraulic cylinders 28 and pistons 29 therefor

between the blocks 22 and 23 are employed to normally maintain the rolls 9 and 10 against their respective backing rolls 7 and 8 in order that these respective pairs of rolls may be in engagement at all times, regardless of the presence of metal between the working rolls.

As best shown in Figs. 1 and 2, the tops 5 of each of the end frames 3 are each provided with two hydraulic cylinders 31 and pistons 32 therefor for bearing on the tops of the corresponding bearing blocks 12 for the backing roll 7. This hydraulic pressure is normally exerted against the backing roll 7 for retaining the working rolls at the adjusted distance of separation for maintaining the thickness of the metal being rolled. The distance between the working rolls is determined by two pairs of adjustable wedges 33 and 34.

The upper wedges 33 are located between the backing roll bearing block 12 and the blocks 17 at each end of the block 12. The lower wedges 34 are located between blocks 18 and backing roll bearing block 13 at the opposite ends of the rolls. A link 35, pivotally connected to each of the upper wedges 33, extends through a slot 36 in the blocks 17 at the other ends of the rolls. The lower wedges 34 are pivotally connected to links 49, and the links 35 and 49 are provided at their outer ends with yokes or clevises 37 and 38, respectively, by means of which they are connected to mechanisms for longitudinal adjustment.

Wear plates 39 are provided between the wedges 33 and the bearing blocks 12 and similar wear plates 40 are provided between the wedges 34 and the cooperating bearing blocks 13.

The mechanism for actuating the wedges 33 and 34 longitudinally to control the distance between the working rolls 9 and 10 is shown in position on the driving side of the rolling mill 115 in Figs. 1 and 2, and in enlarged detail in Fig. 3. This mechanism which is supported by suitable brackets 41, comprises two electric motors 42, one for each pair of wedges, and a worm gear mechanism 43 for each wedge.

As best shown in Figs. 2, 3 and 6, each worm gear mechanism 43 comprises a shaft 44 that is provided with a worm 45 which actuates a worm gear 46. The worm gears 46 are mounted upon screw threaded shafts 47 provided at their outer ends with clevises 48 which are connected to the clevises 37 of links 35, or the clevises 38 of links 49, as the case may be. It will be readily understood that the rotation of the worm gear 46 causes longitudinal movement of the shaft 47 and through the link mechanisms described above the longitudinal actuation of the wedges 33 and 34.

Referring particularly to Fig. 3, it will be noted that the upper motor 42 is connected to a train of mechanism in series comprising a coupling 51, a worm gear mechanism 43 for one of the wedges 33, a clutch 52, a worm gear mechanism 43 for the other wedge 33, a second coupling 51, and a bevel gear mechanism 53 comprising a horizontally projecting shaft 54. The lower motor 42 is connected to a similar train of mechanisms for operating the lower wedges 34.

The bevel gear mechanisms 53 of the upper and the lower trains of mechanisms are connected by means of a clutch 55. The upper clutch 52 may be operated to adjust any difference between the positions of the wedges 33.

Similarly the lower clutch 52 may be operated to adjust any difference between the positions of the wedges 34. The clutch 55 affords a convenient means of adjusting differences between the corresponding positions of the pairs of wedges 33 and 34 in order that the working rolls may be exactly parallel.

It will be noted that the wedge-actuating mechanism or screw-down is open at its central portion to permit access to the ends of the working rolls 9 and 10 to permit driving connections thereto through the opening thus provided.

It will be understood that in the operation of the wedge-actuating mechanism the motors 42 are operated simultaneously and when the clutches 52 and the clutch 55 are in engagement all of the worm gear mechanisms 43 operate simultaneously and to the same extent to adjust the positions of the pairs of wedges 33 and 34. In case of unequal wear, however, such inequality may be compensated for by temporarily releasing either of the clutches 52 or the clutch 55, as the case may be, for appropriate adjustment, in order to insure that the wedges operate to secure uniform spacing of the working rolls 9 and 10.

In order that the spacing of the working rolls 9 and 10 may be readily determined, I have provided indicating mechanism for measuring the distance between the rolls and for indicating also whether or not the working rolls are parallel. The indicating mechanism is best illustrated in Figs. 8 and 9. Attached to the end of each shaft 54 of the wedge-operating mechanism is a worm-gear mechanism 57, the details of which are not illustrated, for operating shafts 58 and 59, respectively.

The shaft 59 is connected by a bevel gear mechanism 60 to a hollow shaft 61, and the latter extends across the front of the mill and is protected by a guard, or shield, 62. The hollow shaft 61 is connected at its right-hand end, as viewed in Fig. 8, to a pointer 63 which operates over the face of a dial 64 that is calibrated in suitable units of distance. The shaft 58 extends through a bearing 66 and the hollow shaft 61, and is connected to a second pointer 67 which also operates in connection with the dial 64.

From the foregoing it will be apparent that the pointer 63 indicates the position of the ends of the working rolls controlled by the wedges 34, while the pointer 67 indicates similarly the position of the ends of the working rolls controlled by the wedges 33. In actual practice when the relative positions of the wedges are accurately adjusted and the rolls are parallel the pointers 63 and 67 will coincide, but they have been shown spaced apart for convenience of illustration. The coincident positions of the pointers also indicate on the dial the distance between the working rolls and accordingly the thickness of the finished sheet metal.

In the operation of the rolling mill of my invention it may be assumed that it is desired to roll sheet metal to a certain thickness. The motors 42 are operated to adjust the wedges until the coincident pointers 63 and 67 indicate upon the dial 64 that the working rolls 9 and 10 have been adjusted to produce metal of that thickness. Fluid pressure is then applied to the cylinders 31 from any convenient source of constant pressure (not shown), such, for example, as that of an accumulator which maintains substantially constant pressure regardless of the

positions of the pistons 32 in the cylinder 31.

This pressure is greater than that normally necessary to maintain the rolls in the positions to which they have been adjusted, and therefore places the housings of the mill under greater stress than would ordinarily be the case during the rolling of the metal. Accordingly, the housing and other portions of the mill are subjected to stress prior to the rolling operation and except as noted below these stresses are not changed by the introduction of the metal between the rolls.

The metal may then be introduced into the rolls and the stress that has been applied to the series of blocks comprising blocks 12 and 13 and intermediate blocks 17 and 18 at each side of each housing is now transferred from the blocks 17 and 18 to the working rolls 9 and 10 and backing rolls 7 and 8. Inasmuch as the pressure necessary to roll the metal is less than that applied to the blocks 12 for the bearing roll 7 by the hydraulic pistons, there will be very slight change in the positions of the working rolls caused by the shift in stresses. It has been determined that the spread of the working rolls due to the pressure imparted to them by the blank being rolled is about one-fourth of the stretch of a roll housing built in the ordinary manner with screws for positioning the upper rolls. The pressure applied to the backing roll 105 bearing blocks 12 is maintained constant by the fluid pressure cylinders 31 whether or not metal is being rolled in the mill.

By referring to Figs. 2 and 4 it will be noted that the cross-sectional areas of the spacing blocks 17 and 18, which are placed under compression by the hydraulic system including the cylinders 31 and pistons 32, are considerably greater than the cross-sectional areas of the vertical posts 4 of the housings 3. The cross-sectional areas of the bearing blocks 12 and 13 are much greater than those of the pairs of spacing blocks 17 and 18 which separate them. In addition, the housings are placed under tension while the bearing blocks and spacing blocks 120 are under compression.

The effect of these differences in cross-sectional areas is to cause the unit stress on the bearing blocks and spacing blocks to be considerably less than that on the housings. In addition, the change in dimensions is less under compression than under tension whereby the shifting of a certain amount of stresses from the spacing blocks and portions of the bearing blocks to the working rolls and backing rolls 130 when metal enters the rolls causes relatively small change in the vertical dimensions of the spacing blocks and accordingly very little change in the adjustment of the positions of the rolls.

In case adjustment of the working rolls is necessary after metal enters the rolls, the screw-down mechanism may be operated at any time during the operation of the mill to make such corrections as may be necessary or desirable.

In case the metal being rolled is unduly cooled and the pressure necessary to roll it to the desired thickness exceeds that for which the hydraulic cylinders 31 are adjusted, the rolls will be forced farther apart, but no additional strain is placed upon the housing or associated parts of the mill because the pressure for resisting this separation does not exceed that of the constant pressure applied to the cylinders 31. Accordingly, breakage, such as usually results from condi-

tions of this character, is substantially entirely avoided.

When the rolling operation has been completed and the fluid pressure applied to the cylinders 31 is released, the pistons 32 are returned to their uppermost positions by discs 69 beneath the lower ends of the pistons, rods 70 and springs 71 that have been placed under compression during the downward movement of the 10 pistons to bear against the bearing roll 7. The springs 71 are of sufficient strength to compensate for the weight of the pistons 32.

The provision of the cylindrical surfaces between the blocks 17 and 18 enables them to adjust their relative positions to maintain full face contact with the cooperating wedges 33 or 34, as the case may be. Unless this adjustment were possible edge contact with the wedges would occur when the rolls were canted which condition is sometimes necessary or desirable. Such relative adjustment may be necessary also because of wear.

It will be noted from the foregoing that I have provided a rolling mill that possesses the 25 advantages of initially placing the housings and other portions of the mill under stress greater than that ordinarily encountered in rolling metal, whereby the stretch or elongation of the housings occurs before the metal enters the mill.

30 The entering of the metal causes a change in stresses in a relatively small portion of the mill. The effect is to very materially diminish any change in the distance between the rolls of the mill caused by introduction of the metal and thereby decrease the variations in the dimensions 35 of the finished metal.

An important advantage of my rolling mill resides in the fact that the pass or opening between the working rolls may be varied before 40 metal enters the rolls, and that stress greater than the rolling pressure may oppose the separation of the working rolls without placing the latter or their bearing blocks under stress until metal enters the rolls.

45 The location of the entire screw-down mechanism on the driving side of the mill is of importance in that all of the assembled rolls and their associated bearing blocks and spacing blocks may be removed as a body from the mill 50 without obstruction and may be assembled without the mill for return thereto as a body. The convenience of this feature will be appreciated by those experienced in the replacement or repair of rolls and associated parts of a rolling 55 mill.

The arrangement for adjusting the distances between the working rolls is simple in construction and effective in operation to secure an 60 accurate adjustment of the working rolls to produce metal of uniform dimensions. The arrangement is such that any variation in the positions of the ends of the working rolls may be readily detected and may be conveniently adjusted for the purpose of providing uniform 65 spacing.

I have provided also a simple and convenient 70 indicating mechanism whereby the relative positions of the ends of the working rolls may be determined at a glance, and whereby the adjustment of the rolls for a desired thickness of metal may be accomplished easily and conveniently.

The foregoing and other advantages will be 75 apparent to those skilled in the art of con-

struction and operation of rolling mills for relatively thin sheet metal.

I claim:

1. A rolling mill comprising a plurality of working rolls, backing rolls therefor, bearing blocks for said rolls, a housing for said bearing blocks, mechanical means for engaging certain of said blocks for adjusting the spacing of said working rolls, fluid pressure devices for placing said housing and certain of said bearing blocks under stress prior to the introduction of metal to the working rolls that is greater than that caused by the introduction of metal, means preventing said stress from being communicated to said rolls and means for adjusting said mechanical means regardless of the application of fluid pressure by said devices. 80

15 2. A rolling mill comprising a plurality of backing rolls, housings for the respective ends of said rolls, bearing blocks for said rolls that are separated by spacing blocks at each end thereof, working rolls between said backing rolls and having bearing blocks located between said spacing blocks, means for placing said housing and said backing roll bearing blocks and said spacing blocks under stress prior to introduction of material to be rolled, and means for adjusting the spacing of the bearing blocks for said backing rolls whereby when metal is rolled between said working rolls, stress is transferred 100 from said spacing blocks to said working rolls. 90

20 3. A rolling mill comprising a plurality of backing and working rolls, bearing blocks therefor at each end thereof, means comprising wedges co-operating with said bearing blocks 110 at each end of said rolls to determine the thickness of the material rolled thereby, and mechanism comprising two pointers for indicating the relative adjustments of the wedges at the respective ends of said rolls and a dial cooperating 115 with said pointers to indicate the distance between the working rolls corresponding to said adjustments.

25 4. A rolling mill comprising a plurality of working rolls, a plurality of backing rolls having bearing blocks therefor at each end thereof, means comprising wedges co-operating with the bearing blocks at each end of the rolls for adjusting the distance between said working rolls to regulate the thickness of the metal rolled 125 thereby, means for adjusting said wedges at the respective ends simultaneously or independently, and indicating mechanism comprising two pointers movable respectively with the adjusting means for the wedges for the respective ends 130 of the rolls, and a dial calibrated in units of distance between said working rolls for co-operating with said pointers.

30 5. A rolling mill comprising a housing, a plurality of backing rolls, bearing blocks therefor 135 at each end thereof, a plurality of wedges comprising spacing elements disposed between and engaging said bearing blocks at each end of said rolls for regulating the relative positions of said rolls to determine the size of the working 140 pass of the mill, and means for adjusting the positions of the wedges at the respective ends simultaneously or independently.

35 6. A rolling mill comprising a housing, a plurality of rolls, bearing blocks therefor at each 145 end thereof, a plurality of wedges at each end of said rolls for co-operating with the corresponding bearing blocks to regulate the relative positions of said rolls, and means for adjusting the positions of the wedges at the respective 150

- ends simultaneously or independently, said means comprising a shaft connected to the wedges for each end and means for detachably connecting said shafts for rotation together.
- 5 7. A rolling mill comprising a housing, a plurality of rolls, bearing blocks therefor at each end thereof, a plurality of wedges at each end of said rolls for cooperating with the corresponding bearing blocks to regulate the relative 80 positions of said rolls, and means for adjusting the positions of the wedges at the respective ends simultaneously or independently, said means comprising a motor for the wedges at each end of the rolls and a detachable clutch 85 for connecting said motors.
8. A rolling mill comprising a housing, a plurality of rolls, bearing blocks for said rolls at each end thereof, means for regulating the distance between certain of said rolls, said means comprising a plurality of wedges for co-operating with the bearing blocks at each end of said rolls, a mechanism for actuating each of said wedges, means for detachably connecting the mechanisms for the wedges at the same ends 90 of the rolls, means for detachably connecting the mechanisms for the wedges at one end of the rolls to the corresponding wedges at the other end of the rolls, and driving means for said mechanisms, whereby said mechanisms may 95 be actuated relatively to each other or simultaneously as desired.
9. A four-high rolling mill comprising two working rolls, two backing rolls therefor, bearing blocks for the respective rolls, a housing for said 100 rolls and said bearing blocks, two wedges disposed between and engaging the bearing blocks for said backing rolls for regulating the distances between the bearing blocks for the backing rolls at each end thereof to thereby regulate 105 the distance between the working rolls, means for actuating the two wedges at each end of the rolls simultaneously or relatively to each other, and means for actuating the wedges at one end of the rolls simultaneously with or relatively to 110 the wedges at the other end.
10. A rolling mill comprising a plurality of 115 backing rolls and of working rolls, bearing blocks at the ends of the respective rolls, blocks for spacing the ends of the backing rolls and having adjacent curved surfaces whereby the spacing blocks may adjust themselves angularly relatively to each other, and means engaging said spacing blocks for controlling the spacing of said backing rolls and for controlling the angular 120 position of said spacing blocks.
11. A rolling mill comprising a plurality of 125 backing rolls and bearing blocks therefor at each end thereof, a plurality of blocks for spacing each of the corresponding ends of said bearing blocks, the spacing blocks having adjacent curved surfaces for relative angular movement, means for engaging said spacing blocks to determine the spacing effected thereby and for controlling the angular position of said spacing blocks, and a plurality of working rolls and bearing blocks therefor located between said spacing blocks.
12. A rolling mill comprising a plurality of 130 working rolls having bearing blocks therefor, a plurality of backing rolls having bearing blocks therefor, and adjustable means disposed between the bearing blocks for said backing rolls for positively varying the distance between said backing rolls prior to the entry of metal between 135
- said working rolls to thereby determine the size of the roll pass formed by the working rolls.
13. A rolling mill comprising a plurality of rolls having blocks certain of which rolls define a pass or opening for metal to be rolled, means for applying a predetermined pressure in excess of the rolling pressure opposing the separation of the pass-defining rolls, means disposed between said bearing blocks for adjusting the positions of said pass-defining rolls and means operable while said pressure is applied for operating said adjusting means.
14. A rolling mill comprising a plurality of working rolls having bearing blocks therefor, a plurality of backing rolls having bearing blocks therefor, and means applying to the bearing blocks for said backing rolls, and without placing said working rolls or their bearing blocks under stress, a pressure opposing the separation of said working rolls which is greater than the pressure required for rolling.
15. A rolling mill comprising a pair of housings, a plurality of backing rolls having bearing blocks, a spacing block between each pair of bearing blocks at the respective ends of the rolls, and means for initially placing said housings, said bearing blocks and said spacing blocks under stress greater than that caused by the rolling pressure when metal is passing through the mill, and said spacing blocks and said bearing blocks being of greater cross-sectional area than said housings, and thereby causing the unit stress on said bearing blocks and said spacing blocks to be proportionately less than that on said housings.
16. A rolling mill comprising a housing, a plurality of rolls therein, means for spacing certain of said rolls, and means operable prior to the entry of metal into the mill for placing said housing and said spacing means under stress 115 that is greater than that caused by the rolling of the metal, said spacing means to which stress is applied having a cross-sectional area that is greater than the cross-sectional area of said housing.
17. A rolling mill comprising a pair of housings, a plurality of backing rolls having bearing blocks, a spacing block between each pair of bearing blocks at the respective ends of the rolls, and means for initially placing said housings, said bearing blocks and said spacing blocks under stress greater than that caused by the rolling pressure when metal is passing through the mill, and the cross-sectional area of said spacing blocks being at least approximately as 130 large as the cross-sectional area of said housings, and thereby causing the unit stress of said spacing blocks to be at least approximately no greater than that on said housings.
18. In a rolling mill a plurality of backing 135 rolls and working rolls, bearing blocks at the ends of said rolls, and spacing blocks disposed between the bearing blocks for said backing rolls provided with curved adjacent surfaces adapted to permit them to adjust themselves angularly 140 relative to each other.
19. In a rolling mill provided with roll housings, a plurality of backing rolls having bearing blocks, a plurality of working rolls, means operable prior to rolling placing said housing and 145 said bearing blocks under stress greater than that caused by the rolling pressure when metal is passing through the mill, and spacing blocks disposed between said bearing blocks for resisting the movement toward each other of said 150

backing rolls and preventing said initial stress being communicated to said rolls.

20. A rolling mill comprising a plurality of rolls having bearing blocks therefor, a housing 5 for each end of said rolls having a window therein for the reception of said bearing blocks, means subjecting said bearing blocks and housing to an initial pressure in excess of the rolling pressure, means preventing said initial pressure being communicated to said rolls and means 10 preventing the rolling pressure from increasing the stress in the housings.

21. A rolling mill comprising a plurality of 15 backing and working rolls having bearing blocks at the ends thereof, a housing for each end of said rolls having a window therein for the reception of said bearing blocks, means for exerting a pressure on said bearing blocks and a tension in said housings in excess of the corresponding 20 stresses produced by rolling, means for preventing the pressure set up by said last-mentioned means being communicated to said rolls, means for preventing the rolling pressure being communicated to said housings, and means for 25 maintaining said working rolls in contact with said backing rolls.

22. A rolling mill comprising a plurality of 30 rolls having bearing blocks therefor, a housing for each end of said rolls having a window therein for the reception of said bearing blocks, a plurality of means at one end of each of said housings for exerting a pressure on the adjacent bearing blocks at opposite sides of the axis of the roll journaled therein, said means being 35 adapted to exert a pressure on said blocks and a tension in said housing in excess of the corresponding rolling stresses, means preventing the pressure exerted by this means being communicated to said rolls, and means preventing the 40 tension established in the housing by said pressure exerting means being increased by the rolling pressure.

23. A rolling mill comprising a plurality of 45 rolls having bearing blocks therefor, a housing for each end of said rolls having a window therein for the reception of said bearing blocks, a plurality of cylinders located at one end of each of said housings and having pistons thereon disposed to bear against the adjacent bearing 50 block at opposite sides of the center thereof, means subjecting each of said pistons to a constant pressure of a sufficient value to exert a pressure on said bearing block and a tension in said housing in excess of the corresponding 55 stresses produced by rolling, and means to prevent the pressure exerted by said pistons on said bearing blocks being communicated to said rolls.

24. In a rolling mill comprising a plurality of rolls, a housing having a window therein for supporting the ends of said rolls, means for setting up a pressure prior to rolling between the ends of said window which is adapted to stress said housing and resist the separation of said rolls without placing the rolls under pressure and which is so disposed as to permit the rolls to assume said pressure when metal is entered between the rolls, and means for maintaining the pressure substantially constant before and after insertion of the metal. 80

25. A rolling mill according to claim 24 including means operable between the ends of the rolls for determining the size of the roll pass.

26. A rolling mill comprising a plurality of working rolls, a plurality of backing rolls having bearing blocks therefor, means located at the opposite ends of said backing rolls for regulating the distance therebetween and determining the thickness of the material being rolled, means for communicating to a common point the movement of the regulating means at both ends of the rolls, and common means cooperating with said last-mentioned means for indicating the position of adjustment of both of said regulating means. 100

27. A rolling mill comprising a plurality of 105 backing and working rolls having bearing blocks therefor and adapted to be driven at one end thereof, a housing for said rolls and said bearing blocks, means disposed between and engaging the bearing blocks for said backing rolls comprising the sole means for regulating the distance between the backing rolls at each end 110 thereof to thereby regulate the distance between the working rolls, and means located at the driven end of the mill for actuating said adjusting means at each end of the rolls simultaneously or relatively to each other. 115

28. In a rolling mill, a plurality of backing 120 rolls and working rolls, bearing blocks at the ends of said rolls, means disposed between and engaging the bearing blocks for said backing rolls which are adapted, when placed under an initial pressure, to reduce the stretching effect of the rolling forces upon the housing.

29. In a rolling mill, the method of preventing the displacement of the working rolls thereof when material is being rolled which consists in placing the supporting housing for said rolls under tension prior to rolling without subjecting the rolls to pressure and preventing the rolling stress appreciably increasing the tension in said 125 housing. 130
